UNITED STATES PATENT OFFICE.

DAVID J. NYSEWANDER, OF TOLEDO, OHIO.

PUMP-OPERATING MECHANISM.

SPECIFICATION forming part of Letters Patent No. 727,189, dated May 5, 1903.

Application filed August 29, 1902. Serial No. 121,512. (No model.)

To all whom it may concern:

Be it known that I, DAVID J. NYSEWANDER, a citizen of the United States, residing at Toledo, in the county of Lucas and State of Ohio, have invented certain new and useful Improvements in Pump-Operating Mechanism, of which the following is a specification.

This invention has relation to pumps of the class chiefly designed to be operated by hand, although applicable to any style or make of pump adapted to be actuated by means of an oscillating handle.

The essential feature of the invention is to reduce the friction to the smallest amount possible and to obtain a maximum movement of pump-rod with a minimum movement of the handle, the parts being arranged so as to obviate any swaying movement of the pump-rod which would tend to cause the bucket or plunger to bind in the barrel and the parts to wear unevenly.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a side elevation of a pump-head embodying the invention, an intermediate portion of the standard being broken away. Fig. 2 is a side view of a cheek of the head-piece applied to the standard. Fig. 3 is a front view of the parts shown in Fig. 1, the actuator being in section. Fig. 4 is a top plan view of the parts illustrated in Fig. 1, showing the head-piece in section.

Corresponding and like parts are referred to in the following description and indicated in all the views of the drawings by the same reference characters.

The pump-head comprises a standard 1, forked at its upper end, as shown at 2, and a head-piece 3, detachably fitted to the fork members 2 of the standard and provided with an opening 4 to guide the rack-bar 5 in its vertical movements. The head-piece 3 is composed of companion parts bolted or oth-

erwise secured together at one end, the remaining portion of the parts being spaced apart to form cheek-pieces 6, between which the toothed actuator 7 at the inner end of the handle 8 operates. Each cheek-piece 6 is provided at its inner end and upon its outer side with a pair of vertical ribs 9, transversely spaced to receive between them the fork members 2 of the standard 1. The inner edges or sides of the vertical ribs 9 are outwardly converged, and opposite edges or sides of the fork members 2 are correspondingly inclined, so as to snugly fit between the ribs 9 and interlock therewith, so as to prevent relative displacement of the parts 2 and 6 after being assembled. To prevent vertical displacement of the head-piece 3, a bolt 10 passes through openings in the parts 2 and 6 in coincident relation. The parts 6 come together at their outer ends and are secured by bolts 11, and their inner sides are recessed to receive the ends of a roller 12, which supports the rack-bar 5 against the outward pressure of the toothed actuator when the pump is in operation. A set-screw 13 is threaded into an opening formed in the outer end of the head-piece, and its inner end is adapted to bear against the roller 12 for adjustment thereof to compensate for wear between the teeth of the parts 5 and 7.

The toothed actuator is approximately of circular form, and a portion thereof only is toothed, the teeth 14 being rollers adapted to turn about their respective axis, so as to minimize the friction when the teeth of the parts 5 and 7 are coming into mesh. The toothed actuator is composed of two parts which are adapted to be secured by bolts or fastenings 15. These parts have a peripheral portion of their opposing sides cut away to receive the roller-teeth 14 and admit of the teeth of the rack-bar 5 meshing with said teeth 14. The walls of the cut-away portion are formed with recesses 16 at regular intervals to receive the ends of the respective roller-teeth 14, whereby the latter are maintained in proper position and mounted to turn when coming into engagement with and leaving the teeth of the rack-bar 5. The center of each part is recessed upon its inner face to receive a series of rollers 17, constituting a roller-bearing for the actuator upon the mounting or bolt 10.

When the parts of the actuator are secured by the fastenings 15, the several rollers 16 and 17 are held in position against casual displacement and are adapted to be removed 5 when required by separation of the parts of the actuator after loosening the bolts or fastenings 15. The toothed actuator is mounted upon the bolt 10 and is provided with the handle 8, which may be of metal or wood and 10 bolted or otherwise attached to said actuator, preferably by being clamped between extensions thereof.

The rack-bar 5 is adapted to move freely through the outer end of the head-piece 3 and 15 is directed in its vertical movements thereby and prevented from any lateral or oscillatory play, thereby causing the bucket or plunger to move rectilinearly without causing unequal wear of the pump barrel or plunger. The 20 pump-rod 18 is secured to the lower end of the rack-bar 5 by means of a clamp-screw 19 in any convenient way. When the bolt or fastening 10 is removed, the actuator 7 and head-piece 3 may be disconnected from the fork of 25 the standard 1. It will thus be seen that the fastening 10 performs a double function—namely, a fulcrum for the toothed actuator and securing means for the head-piece. By 30 having the head-piece separate from the standard the parts may be more cheaply constructed and replaced in the event of breakage or other cause rendering any one of the parts unserviceable.

Having thus described the invention, what 35 is claimed as new is—

1. In a pump-head, and in combination with the standard and vertical reciprocating rack-bar, an oscillatory actuator composed of companion parts, said parts having their inner 40 peripheral portions annularly cut away, the walls of the said cut-away portions being provided at intervals with recesses forming bearings, and roller-teeth located in the cut-away portion of the toothed actuator and having 45 their end portions mounted in the recesses of opposite walls thereof, substantially as set forth.

2. In a pump-head, the combination with a standard bifurcated to form integral fork 50 members, a head portion laterally projected from said members, and a rack-bar mounted for reciprocal movement within said head-piece, of an actuator composed of separable complementary parts having their inner peripheral portions cut away and having opposite walls of the cut-away portions provided

with recesses at intervals thereon, roller-teeth mounted in corresponding depressions and adapted to coöperate with the teeth of the rack-bar, and means for connecting the parts 60 of the actuator, substantially as set forth.

3. In a pump, the combination of a standard comprising spaced parts, a head-piece detachably fitted to the standard and provided with spaced ribs to embrace opposite sides of 65 the respective parts of the standards, a bolt passed through corresponding openings of the head-piece and standard, a rack-bar mounted for rectilinear movement within said head-piece, and a toothed actuator coöperating 70 with said rack-bar and mounted upon the aforementioned bolt, substantially as described.

4. In a pump, the combination of a standard comprising spaced members, a bolt supported by means of said members and extended across the space formed between them, a rack-bar, an actuator coöperating with the rack-bar and comprising complementary parts having a peripheral portion and the central portion of each cut away upon its inner face, said actuator being mounted upon the aforementioned bolt, rollers located in the central space formed by the central cut-away portions of the parts, and roller-teeth mounted 85 in the walls of the peripheral cut-away portion of said parts, substantially as specified.

5. In a pump-head, a standard having its upper end forked, a head-piece composed of cheek-pieces coming together at one end and 90 provided with spaced ribs at the opposite end to receive the fork members, the opposing sides of the ribs being converged to interlock with corresponding sides of said fork members, a bolt passed through corresponding 95 openings of the fork members and cheek-pieces, a roller confined between the outer ends of said cheek-pieces, means for adjusting said roller, a rack-bar mounted to reciprocate rectilinearly within said head-piece, an actuator mounted upon the aforementioned 10: bolt and comprising complementary parts having a central and peripheral portion cut away, and rollers mounted in the cut-away parts comprising the actuator, substantially 105 as specified.

In testimony whereof I affix my signature in presence of two witnesses.

DAVID J. NYSEWANDER. [L. S.]
